UNITED STATES PATENT OFFICE.

JOSEPH C. CAIN, JR., OF FORD, KENTUCKY.

MAIL-BAG CATCHER.

Application filed August 27, 1921. Serial No. 495,949.

To all whom it may concern:

Be it known that I, JOSEPH C. CAIN, Jr., citizen of the United States, residing at Ford, in the county of Clark and State of Kentucky, have invented certain new and useful Improvements in Mail-Bag Catchers, of which the following is a specification, reference being had to the accompanying drawings.

10 It has been found that when a train is slowing down to make a stop at a station, the mail bag very often slides off the old form of hook carried by a mail car, necessitating the station master picking the bag up and 15 throwing it in the mail car, that is if the station master is not very busy. Occasionally the mail bag or sack slides or drops off the hook when the train is passing by the station, and in this case the mail will have 20 to lay over until the next train, causing several hours delay.

The present invention has for its purpose to provide a mail bag catcher, which is simple, efficient and practical in construction, 25 and especially adapted for overcoming the mail bag sliding or dropping from the catcher.

With this end in view, another purpose is to provide a mail bag catcher, wherein a pair 30 of clamping jaws is provided one being automatically actuated by the act of a mail bag contacting with hinge connectors of the clamps, permitting one of the clamps to be drawn toward the other, clamped by means 35 of spring means, thereby clamping the mail bag securely between the two jaws.

Still another purpose is the provision of means manually actuated for opening the 40 spring tensioned movable clamping jaw, so that the hinge links will automatically open and hold the spring tensioned clamping jaw open, whereby the mail catcher can be operated for the next mail bag or sack.

A further purpose is the provision of 45 means for reinforcing the stationary jaw, and mounting the mail catcher on the usual transverse rod mounted in the opposite sides of a door opening of the mail car.

While the design and construction at present illustrated and set forth are deemed preferable, it is obvious that as a result of a reduction of the invention to a more practical form for commercial purposes, the invention may be susceptible of changes, and the 55 right to these changes is claimed, provided

they are comprehended within the scope of what is claimed.

The invention comprises further features and combination of parts, as will be herein-after set forth, shown in the drawings and 60 claimed.

In the drawings:—

Figure 1 is a view in perspective showing the mail catcher as applied to a door opening of a mail car, showing the mail catcher 65 in a position ready to receive the mail bag;

Figure 2 is a transverse sectional view on line 2—2 of Figure 1, showing the relative proportions of the mail catcher, so that it may be swung through the door opening; 70

Figure 3 is a sectional view on line 3—3 of Figure 2; and

Figure 4 is an enlarged detail view of one arm of the lever 30, showing its ball bearing roller 31.

Referring to the drawings, 1 designates a portion of the mail car provided with a door opening 2, and journaled in bearings of plates 3 (which is secured to the jambs of the door opening) are the reduced ends 4 of a 80 transverse rotatable or rocking rod 5. This rod carries the right angle extending arm 6, which is fixed as at 7, by brazing or otherwise to the rod 5, and is adapted to carry the mail catcher. This arm 6 may be otherwise 85 fastened on the rod, there being a suitable brace 8, which is connected at 9 in any suitable manner to the arm, and brazed or otherwise connected at 10 to the rod, so as to reinforce the arm, whereby it may withstand 90 the force of the mail bag or sack engaging the mail catcher.

The mail catcher comprises stationary and movable clamping jaws 11 and 12, the former being fixed at 13 to the arm 6, and reinforced by the braces 14, which are disposed angularly relatively to the arm 6 and the stationary clamping jaw 11. The movable jaw 12 is hingedly connected at 15 to the arm 6, and when opened, it is designed 100 to assume an acute angle relatively to the jaw 11.

The two jaws are provided with slots 16 and 17 in which the links 18 and 19 are pivoted as at 20. The links 18 and 19 are in 105 turn pivotally united as at 21, there being abutting shoulders 22 adjacent the pivot 21, to prevent the links 18 and 19 from pivotally collapsing in the direction of the arrow α . However the links 18 and 19 are capa- 110

ble of pivotally collapsing in the opposite direction, particularly when a mail bag comes in contact therewith, so that the movable clamping jaw may collapse toward the 5 stationary clamping jaw, thereby permitting the mail bag to be clamped between the two jaws. When the movable clamping jaw moves toward the stationary clamping jaw, the slots permit the links to substantially 10 completely collapse, so that the movable clamping jaw may move to a closed position relatively to the stationary clamping jaw.

A pair of elongated bolts 23 engage through 15 the stationary clamping jaw and are provided with nuts 24, on the opposite sides of the jaw to hold the bolts 23 rigid relatively to the stationary jaw. These bolts 23 operate through the elongated opening 25 in 20 the movable clamping jaw, there being coil springs 26 interposed between the outer face of the movable clamping jaw and nuts 27 on the ends of the bolts 23, so as to operate the movable clamping jaw toward the stationary 25 clamping jaw, when the links 18 and 19 come in contact with the mail bag or sack, usually suspended from the conventional form of mail crane on the side of the track. The bolts 23 are provided for the purpose of 30 guiding the movable clamping jaw toward and from the stationary clamping jaw, and acting to hold the jaw 12 in position relatively to the stationary jaw 11, and particularly to withstand the strain. Furthermore 35 the bolts 23 act to support the coil springs.

The stationary jaw 11 has a slot 28, in which as at 29 an angle lever 30 is pivoted. One arm of the lever carries a ball bearing mounted roller 31, which is designed to engage 40 the movable clamping jaw 12, for the purpose of opening the same, to set it, whereby the links 18 and 19 are held in alignment, so as to be engaged by the mail bag. A coil spring 32 connects the other 45 arm of the lever 30 and the arm 6, and acts to restore the lever 30 to its initial position, for opening the movable jaw 12.

It will be noted that when the mail car is approaching the mail crane at the station 50 with the mail bag supported thereon, the railway mail clerk in the mail car moves the arm 6 outwardly at right angles to the door opening, positioning the mail catcher laterally of the car. However before disposing 55 the mail catcher in this position the movable clamping jaw is opened, by actuating the lever 30 in the direction of the arrow *b*, in which case the ball bearing mounted roller 31 will engage and slide upon the jaw 12, and 60 dispose it in an acute angle relatively to the stationary jaw 11, in which case the links 18 and 19 will assume the position shown in Figure 1. However the jaw 12 is opened by actuating the lever 30, the spring 32 will 65 act to restore the lever 30 to its initial posi-

tion. When the mail bag contacts with the links 18 and 19, they will collapse in a direction opposite the direction indicated by the arrow *a*, allowing the movable clamping jaw to move toward the stationary clamping jaw 70 and clamp the mail bag or sack between the two jaws. Then the mail catcher may be swung downwardly, or upwardly toward and through the door opening of the mail car, where the mail clerk may remove the sack, 75 and then restore the movable clamping jaw 12 of the mail catcher to its initial position ready to catch the next mail bag or sack.

It is obvious that the mail catcher is made in such proportions and disposed relatively 80 upon the arm 6, so that when the arm 6 is moved and the shaft 5 rocked, the mail catcher may be swung inwardly of the door opening in order that the mail bag or sack may be detached.

Connected to the outer remote ends of the links 18 and 19 are springs 34, which in turn are connected at 35 to the outer faces of the jaws 11 and 12, in order to move the links to an open position, when the jaw 12 is 90 opened. Also when the links 18 and 19 are open, they assume a slight obtuse angle, with the abutting shoulders 22 of the links positioned slightly forwardly beyond and out of alignment with the pivots 20, said 95 springs 34 acting to hold said links in such positions. However as soon as the mail bag comes in contact with the links 18 and 19, the links are tilted rearwardly, allowing the jaw 12 to close and clamp the bag.

The invention having been set forth, what is claimed as being useful is:

1. In a mail bag catcher, a rocking support adapted for mounting in a horizontal position and connecting the opposite jambs 105 of a door opening of a mail car, of an arm movable with said rod, stationary and pivoted clamping jaws carried by the arm, one extending in a plane parallel with the car, the other extending at an acute angle to the 110 frame of the car, a pair of parallel rods secured to the stationary jaw and engaging through the pivoted clamping jaw, coil springs mounted upon the extremities of said parallel rods, means for tensioning said 115 springs, whereby the springs will actuate the pivoted clamping jaw to move it toward the stationary clamping jaw, the stationary and pivoted clamping jaws provided with 120 slots, extensible and collapsible means pivot- 125 ed in said slots and connecting the stationary and pivoted jaws and adapted to hold the pivoted jaw open, whereby upon the mail bag contacting with said extensible and collapsible means, the pivoted jaw may close toward the stationary jaw, thereby adapted to clamp a mail sack, springs connected to the remote ends of the extensible and collapsible means to hold said means extended, and an angular spring tensioned lever carried by 130

the stationary jaw to open the pivoted clamping jaw.

2. In a mail bag catcher, the combination with a rocking rod adapted for detachable mounting in a horizontal position between opposed supports, of an arm movable with said rocking rod, stationary and pivoted clamping jaws, the stationary jaw being fixed to said arm in a plane parallel with the car, the pivoted clamping jaw being mounted on the arm to assume an acute angle to the stationary jaw when open, spring-tensioned means connecting the two jaws to actuate the pivoted clamping jaw toward the stationary clamping jaw, the clamping jaws having elongated slots, extensible and collapsible members pivoted together and

pivots mounted in said slots and connecting said jaws, tensioned means connected to the remote ends of the extensible and collapsible members and in turn connected to the jaws, the construction and arrangement of the pivotal connection between said members being such that together with the tensioned means, the pivoted jaw may be held open, whereby upon engagement of a mail bag with said extensible and collapsible members, the pivoted clamping jaw will close and grip a mail sack to the stationary jaw, and manually actuated means for opening the pivoted clamping jaw.

In testimony whereof I hereunto affix my signature.

JOSEPH C. CAIN, JR.
